MANUFACTURE OF WARP GOODS

Paul Schönfeld, Chemnitz, Germany

Application May 21, 1932, Serial No. 612,790
In Germany July 13, 1931

3 Claims. (Cl. 66—84)

This invention relates to a method of producing ribbed two-machine warp goods on a frame having only one row of needles.

Ribbed warp goods were hitherto made exclusively on frames having two rows of needles, and the invention makes it possible for the first time to produce such goods, especially transversely ribbed goods, on a machine having only one row of needles. According to the invention, a ground fabric is lapped first with the upper machine, for instance in the form of a simple tricot lap, under 1 over 1 and back, while the lower machine, in order to form ribs, places the threads under the needles, e. g. under 2 and back, so that during these operations the lower machine is racked alternately once in the same direction as the upper machine and then again in a direction opposite to the latter.

One form of the invention is illustrated in the accompanying drawings, in which Figure 1 is a lapping diagram, Fig. 2 indicates the way of looping, only one thread of the lower machine being shown for clearness' sake,

Fig. 3 is a diagrammatic view showing parts of the upper and lower machines in producing the goods of Fig. 2, and Fig. 4 is a similar view for producing the goods of Fig. 1.

The upper machine or row of guide needles produces with its thread 1 the ground fabric, such as a plain tricot (under 1 over 1 and back) while the lower machine 2, in order to form ribs with its threads 2 operates under the needles, such as under 2 and back. As the arrows in Fig. 1 indicate, the lower machine with the threads 2 will be racked once in the same direction as the upper machine with its threads 1 and then again in a direction opposite to the latter. The change in the direction of motion of the lower machine relative to that of the upper machine may be effected in any suitable way, by omitting for example to laterally rack the lower machine with its threads 2 for an odd number of courses.

The lapping diagram according to Fig. 1 shows how the lower machine or row of guide needles is racked in the six courses *a* in the same direction as the upper machine. In the course *b* the lower machine is not racked laterally at all and in the three following courses *c* the lower machine is racked in a direction opposite to that of the upper machine. In the next course *b* lateral racking of the lower machine is omitted, so that the lower machine in the connecting six courses *a* of the next repeat may be racked again in the same manner as the upper machine.

Racking, which takes place, for the purpose

of forming ribs, alternately in the direction of the upper machine and then again opposite to the latter, involves alternate throwing up of the goods towards the rear and front side. The reasons are chiefly found in the fact that only the threads 2 of the lower machine are placed under the needles to form ribs. In this way these threads 2 are not stitched on to one side of the goods so to speak, as is the case with plain cord with lining, but the threads 2, as clearly indicated in Fig. 2, interlace in the ground fabric. This interlacing takes place according to known principles in such a way that the threads 2 at the points where they are racked in the same direction as the threads 1 of the upper machine embrace from the left-hand side the connecting portions 3 of the meshes of the ground fabric and in this manner put the ground meshes at these points in oblique position, which naturally causes the goods to incline towards the right-hand side. On the other hand, at the points where the threads 2 are placed in opposite direction to the threads 1 of the upper machine the threads 2 will come under the connecting portions 3, and they will hang on to the mesh heads 4 of the meshes produced by the needles under which the threads 2 have been placed and thus draw these meshes into an approximately vertical position, so that the goods at this point are thrown to the rear side. The ribs in the goods will therefore extend in the direction of the courses.

Whenever desired, the lower lapping machine can also lap over the needles at points in addition to lapping under them except at points where the lower machine has to form ribs.

Warp goods produced in the manner indicated, if made of artificial silk, afford, above all, the advantage that they will not lose their elasticity after washing like the known kinds of ribbed goods.

In the method of this invention it is to be understood that there are only two thread groups 1 and 2. There is no third group of threads. The numeral 3 in Fig. 2 of the drawings merely designates parts of the threads 1, namely, those parts of this thread which connect with each other the separate stitches in the finished fabric.

I claim:—

1. A method of producing transversely ribbed warp fabric by means of two lapping machines on a warp loom having only one row of needles, comprising lapping a ground fabric with the upper machine and carrying out underlying operations with the lower machine to form ribs, the

lower machine being alternately racked during a number of courses in the same direction as the upper machine and in the opposite direction thereto.

5 2. A method according to claim 1, in which the racking of the lower machine is omitted for an

odd number of courses and then racked in the opposite direction to the upper lapping machine.

3. A method according to claim 1, in which the underlaying operations of the lower machine are produced on at least two needles.

PAUL SCHÖNFIELD.
